US00D761339S

(12) **United States Design Patent**
White, Jr. et al.

(10) **Patent No.:** **US D761,339 S**
(45) **Date of Patent:** **** Jul. 12, 2016**

(54) **COMPLIANT MANUFACTURING ROBOT**

(71) Applicants: **Robert White, Jr.**, Roslindale, MA (US); **Waleed A. Farahat**, Newton, MA (US); **Michael Sussman**, Winchester, MA (US); **Elizabeth Goodrich**, Roslindale, MA (US); **Peter Swai**, Weymouth, MA (US); **James F. Daly, III**, Groton, MA (US)

(72) Inventors: **Robert White, Jr.**, Roslindale, MA (US); **Waleed A. Farahat**, Newton, MA (US); **Michael Sussman**, Winchester, MA (US); **Elizabeth Goodrich**, Roslindale, MA (US); **Peter Swai**, Weymouth, MA (US); **James F. Daly, III**, Groton, MA (US)

(73) Assignee: **Rethink Robotics, Inc.**, Boston, MA (US)

(**) Term: **14 Years**

(21) Appl. No.: **29/520,631**

(22) Filed: **Mar. 17, 2015**

(51) LOC (10) Cl. **15-99**

(52) U.S. Cl.

USPC **D15/199**

(58) **Field of Classification Search**

USPC D15/199; D21/578
See application file for complete search history.

(57) **CLAIM**

The ornamental design for a compliant manufacturing robot, substantially as shown.

DESCRIPTION

FIG. 1 is a perspective view of a compliant manufacturing robot incorporating the design

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

1 Claim, 7 Drawing Sheets

FIG. 1

FIG. 2

FIG. 3

FIG. 4

FIG. 5

FIG. 6

FIG. 7
